United States Patent Office.

HENRY M. QUACKENBUSH, OF HERKIMER, NEW YORK.

Letters Patent No. 70,016, dated October 22, 1867.

IMPROVED EXTENSION-LADDER.

The Schedule referred to in these Letters Patent and making part of the same.

TO ALL WHOM IT MAY CONCERN:

Be it known that I, HENRY M. QUACKENBUSH, of Herkimer, in the county of Herkimer, and State of New York, have invented a new and useful improvement in Extension-Ladders; and I do hereby declare that the following is a full, clear, and exact description thereof, which will enable others skilled in the art to make and use the same, reference being had to the accompanying drawings, forming part of this specification, in which—

Figure 1 is a front elevation of my ladder.

Figure 2 is a longitudinal section, taken in the plane of the line xx , fig. 1.

Figure 3 is a detached view of the clip for holding the sliding part of the ladder to the stationary part.

Figure 4 is a view of the hook detached from the ladder.

Similar letters of reference indicate like parts.

My invention consists in a novel arrangement of the parts of an extension-ladder, whereby the extension may be operated easily and be held firmly in position.

A designates the stationary ladder, and B the sliding ladder. The ladder B carries at its lower end, on each side, a clip, a, which is secured to the sliding ladder B, and passes over the outside of the ladder A, and is bent up on the under side, so that it holds the ladders together, but at the same time permits the ladder B to be slid up and down. The ladder A carries at its upper end a similar clip, b, but in this instance the clip is fastened to the ladder A, and passes over the outside of the ladder B, and is bent up so as to hold the two together, and, like the former instance, permits the ladder B to have a sliding motion.

C is a cord or rope, which is fastened to the lower end of the ladder B, and passes through a pulley, c, secured to the ladder A, near its top end, and the rope then passes down and is thrown over, say the lower round of the ladder A, and the end fastened to the lower end of the ladder B. Thus, to slide upward the ladder B, it is only necessary to draw down upon the rope or cord C, say at or about the point indicated by the letter z.

D is the hook for holding the ladder B at any point it may be desired to raise it. I have represented but one hook secured to one side of the ladder, as shown in fig. 2, but there may be another on the opposite side of the ladder, or others along the length of the ladder, if it be found that one or two are not sufficient to sustain important feature of my invention, and is shown clearly in figs. 2 and 4, fig. 2 showing one side and fig. 4 the other. This hook, as before stated, is secured to the side of the ladder B, and a spring, d, is applied in such manner as to cause the hook to be always thrust forward. In sliding upward the ladder B the bevelled end e of the hook strikes the rounds of the ladder, and thus throws the hook out of the way at each successive round; but when it is desired to cause the hook to catch upon the desired round the hook is thrown just above the round and then allowed to fall over it. A guard-finger, f, is pivoted to the hook on its outer side, which is so made as to naturally fall downward, as represented in fig. 2, and thus not at all interfere with the operation of the hook when sliding up the ladder B. Now, when the ladder B is to be lowered, this finger is raised by striking against the rounds, and this throws the hook out of the way, and the ladder is slid down readily. The hook D is disengaged from the round on the ladder A, on which it rests, when it is desired to lower the ladder B, by first elevating or sliding the ladder B so as to bring the guard-finger f above the round. This extension-ladder is simple in all its features, and it can be worked easily, and none of its parts are likely to get out of order.

What I claim as new, and desire to secure by Letters Patent, is—

1. The hook, having an inclined top, e, in combination with the spring d and parts A and B of the ladder, substantially as specified.

2. I claim the guard-finger f, in combination with the hook D and parts A and B of the ladder, substantially as specified.

3. I claim the spring d, or its equivalent, in combination with the hook D, substantially as specified.
